REGISTER SWITCH UTILIZING A PLURALITY OF DISCHARGE TUBES

Martinus den Hertog and Lucien Alfred B. Cabes,
Antwerp, Belgium, assignors to International
Standard Electric Corporation, New York, N.Y.,
a corporation of Delaware

Application May 8, 1943, Serial No. 486,275
In the Netherlands July 11, 1941

Section 1, Public Law 690, August 8, 1946
Patent expires July 11, 1961

12 Claims. (Cl. 179—18)

1

This invention relates to new and useful improvements in electrical switching devices which may be used, e. g. in telephone systems or similar systems, and more particularly to special devices for the electrical control of moving apparatus, in which the switching time must be reduced to a minimum.

The object of the invention is to obtain the required accuracy of setting of apparatus which is operated at the greatest possible speed. This is accomplished by using electrical discharge tubes to control the operations.

According to one of the features of the invention two or more electrical discharge tubes are used in combination for the control of a switching apparatus, one of these tubes controlling the moving mechanism of a switching apparatus, and being controlled in turn by the other tube or tubes in accordance with the position reached by the apparatus.

According to another feature of the invention, the power magnet of a switching apparatus is energized in series with the discharge space of a vacuum tube and the switch is put into motion and the control of a grid to which through a condenser a potential is applied to operate the tube.

According to a further feature of the invention the operation of the first tube is interrupted when the second tube starts upon the desired setting of the moving apparatus. The interruption is caused by a brief decrease of the potential applied to the discharge space of the first tube by the change of the charge of a condenser, which is connected between electrodes of the first and second tubes.

The invention will be described with reference to the drawings in which Fig. 1 diagrammatically illustrates the circuit of a register controller for a group selector such as is used in telephone systems or the like for the selection of a free outlet in a desired group, and Fig. 2 illustrates the register circuit of a selector adapted to select outlets from alternative groups.

As well-known, automatic telephone selector switches and the like may be controlled by means of cold-cathode tubes. The United States patent applications of Kruithof et al. 472,624, filed January 16, 1943, and 473,278, filed January 22, 1943, describe such devices, in which a cold-cathode discharge tube is used, together with a relay connected in series with the discharge space of the tube. A contact of the relay is connected in series with the circuit controlling the switch, and when the switch arrives in a predetermined position in which the tube functions,

2

the relay in series with the discharge space operates and causes the switch to stop.

In such devices the relay serves therefore as a test relay because it operates when the switch finds a free outlet in a required group and stops the switch. In such devices use may be made of free test potentials derived from a direct current course or an alternating current source and both arrangements are applied to some of the embodiments described in said patent applications.

The combination of a cold cathode tube with a relay insures quicker operation than a relay connected directly in series with the free test potential.

This is so because the tube operates practically without any delay (in about 10^{-4} sec.) and permits the connection of the test relay in a circuit independently of the test potential. All arrangements made be made for a quick operation of the relay, e. g. by applying a high potential, by connecting in series a resistance shunted by a condenser, etc.

The very short time in which the test relay in these arrangements attracts its armature, is of very great importance if the switches operate at very high speed, e. g. 100 contact sets per sec. or more. At such speed the time between the engagement of two consecutive contact sets is 100 milli-seconds or less, but the time available for the energizing of the test relay is only a small fraction of this because a continuously moving switch must be stopped between the first engagement by the test brush of the test contact and the moment when the brush is about half-way over the contact. At a speed of 100 contacts this time interval will amount to about 3.5 milli-seconds, during which the relay must attract its armature and stop the switch by de-energizing the power magnet and braking of the rotor.

Even an operating time of 1 milli-second for the test relay will leave little time available for safely and accurately stopping the switch.

The invention makes possible the stopping of a hunting switch without energizing a test relay. A gaseous discharge tube controlled by a grid, a so-called "thyatron," is used in conjunction with a cold-cathode tube in such a way that the latter responds to the signal received from the switch, indicating that the desired outlet is reached, and the "thyatron" stops the switch by opening the circuit controlling it.

Fig. 1 shows part of a register controller and a selector switch as described in the above-mentioned United States patent application 473,278

filed January 22, 1943. The principal difference between Fig. 1 and the embodiment shown in said application consists in that the tube T_y is added together with the condensers C_1 , C_2 , C_3 and the resistances R_1 , R_2 , R_3 , R_4 . Further small differences, which are not of an essential importance for the invention, will become clear from the further description.

The tube T_y is a gaseous discharge tube with an indirectly heated cathode containing as further electrodes a grid and a plate or anode. The grid is connected to a potential which is negative with respect to the cathode and high enough to prevent the starting of the ionization of the discharge space. Once the discharge has started, the continuance thereof is not influenced by the potential of the grid, but is dependent solely on the potential between cathode and anode. The extinguishing of the discharge takes place only when the cathode-anode circuit is interrupted, or when the potential between these electrodes is decreased below a critical discharge potential. With a tube of this type, which may allow a rather high current to pass, it is possible to control a magnet of a selector switch in the manner described below.

Starting of the selection

The starting of the movement of the selector switch is determined by the closure of ground at a register switch marked a , whereby relay Chr is energized in the circuit: ground via brush and terminal of bank a of switch OM , back contacts of Vrr , Str and Ftr , winding of Chr to battery.

The operation of relay Chr causes the anode and cathode circuits of the cold-cathode tube T_2 to close, whereby this tube is prepared to respond to a signal received from a selector switch. Moreover, relay Chr makes a connection to ground, by which condenser C_1 is charged in series with resistance R_2 . This condenser is normally kept in a discharged condition over the resistances R_2 and R_3 in series. The charging of C_1 causes a short decrease of the negative potential on the grid resistance R_1 of thyatron T_y . This decrease of potential is sufficiently large to discharge the thyatron. After a very short time the condenser C_1 attains its full charge and the potential on the grid resistance is restored to the original value. This potential has, however, no further influence on the discharging of the tube. The time of lighting the thyatron takes practically no time (of the order of 10^{-6} sec.) The condenser C_1 may be chosen very small and the entire charging process thereof, and the change of potential on the grid via the grid resistance R_1 may be completed in one milli-second or less. Thus almost immediately after the ionization of the thyatron it may be extinguished and the potential on the grid will not produce a new discharge, because the condition which caused the first discharge was immediately removed.

As soon as the tube T_y is ionized, current flows in the circuit: negative battery -130 volts via cathode, discharge space and anode of T_y , resistance R_4 , power magnet P to ground.

The resistance R_4 is connected in parallel to a condenser C_3 , which is normally discharged by this resistance. When current begins to flow through the discharge space and the power magnet of the selector, first condenser C_3 will be charged and, as C_3 has a rather high capacity, the current in P will rise to a relatively high value and will then decrease slowly to the poten-

tial at the terminals of R_4 until C_3 is charged. The value of C_3 is selected so that the duration of the increased current is sufficiently long fully to energize the power magnet P . The power magnet is so adjusted that pulling up of the armature takes place only at this enlarged current, but not at the current flowing while C_3 is charged. This current is determined by the value of R_4 and is sufficient to keep the armature of the power magnet pulled up, once it is energized. When the selector is stopped, the value of the magnetic field in the power magnet will already be much decreased, and the magnet armature will therefore release very quickly.

Alternating current test of selector switch

The controlling electrode of the cold-cathode tube T_2 is normally connected over a high resistance and a second resistance of 15,000 ohms to a potentiometer, consisting of three resistances of 7500, 2500 and 7500 ohms. The potential connected to the controlling electrode by means of this potentiometer via the back contact of relay Wr is such, that ionization of the tube T_2 will occur if this potential is not decreased by a rectified alternating current supplied by the rectifier bridge Re in series with a retardation coil RC to the resistance of 15,000 ohms. The direct current potential obtained from the rectifier Re is normally of opposite direction to that obtained from the potentiometer. In the known way, the alternating current connected to rectifier Re will decrease to zero only by the receipt of a signalling current in the transformer HC_1 , which has the same characteristics as the reference current which is supplied to the transformer HC_2 , so that it cannot supply direct current to the resistance of 15,000 ohms. The potential of the controlling electrode is then increased to the potential supplied by the potentiometer, and the cold-cathode tube is ionized.

At the moment the selector switch reaches an outlet in the desired group, an alternating current with a certain phase difference is applied via the "d" brush of the selector switch and by the primary winding of transformer HC_1 . In the above-indicated way the tube T_2 is then ionized, whereupon current flows from -130 volts via: front contact of Chr , cathode, discharge space and anode of T_2 , front contact of Chr , winding of Vtr to ground.

As a result of the closure of this circuit, the potential on the anode of T_2 , which till this moment was equal to the ground potential, is increased to a value which is equal to 130 volts, less the potential of the tube T_2 , which amounts to about 73 volts. This increase of about 55 volts of the potential of the anode of T_2 causes a charge displacement of the condenser C_2 . Since the anode gets a negative charge, an impulse of negative direction is applied to the plate of the thyatron T_y for a short time. The potential of this plate with respect to the potential of the cathode of the thyatron is decreased to such an extent that the discharge of the thyatron is suddenly interrupted, because the potential falls below the critical point at which discharge is still possible. As the grid of the thyatron is constantly negative with respect to the cathode, the discharge cannot start again when the negative pulse to the plate is at an end. The current through the power magnet P is, therefore, very quickly interrupted, i. e. at the speed of the deionization time of the thyatron, which amounts to approximately 10^{-4} per second. In this way

the rotor or brush carriage of the selector switch stops on the set of contacts belonging to an outlet in the desired group.

Repetition of the alternating current test

It is possible that the alternating current is connected to an outlet when the wipers of a selector switch have almost passed the terminals of this outlet. In this case the tube T_2 will still respond, but it is not sure that the rotor will still stop before the brushes leave the terminals. In order to determine whether the rotor has stopped on these terminals, the alternating current test is repeated after the rotor has stopped, and if it appears that no alternating current potential is present on the "d" terminal, then the hunting movement starts again. This takes place as follows:

The response of tube T_2 causes also the energizing of relay Vtr in series with the discharge space. Relay Vtr closes the following circuit for the energizing of relay Ftr : ground, front-contact of Vtr , back contacts of Gbr and Fhr , winding of Ftr , to battery.

Relay Ftr prepares a temporary locking circuit for itself, in series with the winding of relay Fhr ; but as long as relay Vtr is energized, Fhr cannot operate. Relay Ftr opens also the circuit for relay Chr , which is then released and opens the cathode and anode circuits of tube T_2 . The tube T_2 is thus extinguished and relay Vtr released.

Upon the release of relay Chr the condenser C_1 , which was kept charged via a front contact of relay Chr , may now discharge via the resistances R_2 and R_3 .

Upon the release of relay Vtr relay Fhr energizes and this relay again closes the circuit for relay Chr . This relay now again closes the cathode-anode circuits of tube T_2 and also the following circuit for relay Kir : ground to back contact of Vtr , front contacts of Chr and Ftr , windings of Kir , battery.

As soon as the brushes of the selector switch are on the set of contacts of the desired outlet, tube T_2 will immediately respond again and relay Vtr will be energized. This relay then opens over its back contact the operating circuit of relay Kir . If, however, tube T_2 does not respond, relay Kir energizes and closes an operating circuit for relay Vrr , which releases the two relays Ftr and Fhr by interrupting the locking ground. Relay Vrr also releases relay Chr , by which the circuit for relay Kir is opened. Relay Kir releases and also Vrr , which now again closes the circuit for relay Chr . Since relay Chr is operated the hunting action can again start by the charge of condenser C_1 .

Direct current test

After the termination of the alternating current test, the register tests whether a free direct current potential is present on the terminal on which the selector switch stopped. If this is the case, the outlet is definitely seized and the hunting selector switch is connected through by operating its relay Br . In the absence of direct current potential on the selected terminal, the selector switch must continue hunting. This must take place also in case alternating current potential is present on the "d" terminal, and it must be possible for the selector switch to stop on the next terminal to which this potential applied. This happens as follows:

In the second alternating current test, relay Vtr operates for the second time and energizes

relay Str in the following circuit: ground, front contact of Vtr , back contact of Gbr , front contact of Fhr , winding of Str , battery.

Relay Str closes a temporary locking circuit for itself under the control of a back contact of relay Wlr to a back contact of relay Vrr . It opens ground for relay Chr , whereupon this relay releases and tube T_2 extinguishes. Furthermore, it connects the windings of the test relay Tr to the "c" brush of the switch via a back contact and winding of relay Br . The direct current potential, if present at the outlet, is connected to the "c" contact and relay Tr operates in the known way in series with relay Br . By operating relay Tr a circuit of low resistance is closed over windings of Dtr and Tr , by which the free test potential to the "c" brush is decreased to a value at which other test relays cannot operate. The operating of Dtr is, therefore, the signal that the free outlet is definitely seized and this causes the operating of relay Sar , which now connects the register to the position in which the next selection can be performed by the stepping movement of the wipers of switch OM . Relay Vrr is operated by relay Sar , whereupon the relays Ftr and Fhr release. Relay Str is kept operated by relay Sar , until the magnet of switch OM is fully energized and the switch opens its interrupter contact, and until relay Dtr is released. This takes place when the circuit for the free test potential is opened at the seized outlet.

If, however, for some reason no free test potential is present at the outlet, e.g. because the fuse blew, relays Tr and Dtr do not operate and the following circuit is closed for the slow operating relay Gbr : ground to front contact of Str , back contact of Tr , winding of Gbr , battery.

Relay Gbr closes a temporary locking circuit for itself to ground over the back contact of relay Vrr and in turn operates relay Wlr . This relay opens in a back contact the energizing circuit of relays Ftr , Fhr and Str . Upon the release of relay Str a circuit is again closed for relay Chr , which connects again the anode and cathode circuits of tube T_2 . The conditions under which tube T_2 operates are now, however, changed by relay Wlr as compared to those that existed when relay Chr was not energized. In the first place, the controlling electrode of T_2 is now connected to another point of the potentiometer, the potential at which is such that it alone cannot produce the ionization of tube T_2 . In the second place, relay Wlr has now interchanged, via two change-over contacts, the connections of the rectifier bridge to the 15,000 ohm resistance. If now alternating current is received by the rectifier bridge, the direct current delivered thereby will be of the same direction as the direct current derived from the potentiometer. At that moment two cases may occur:

(a) At the seized outlet the alternating current may still be present, notwithstanding the fact that no direct current was found.

In this case the alternating current obtained from the outlet is equal to the reference potential whereby no alternating current will be delivered to the rectifier. Tube T_2 can, therefore, not respond. When relay Chr is now energized, condenser C_1 is again charged via the front contact of relay Chr and tube T_2 is again ionized, whereupon the power magnet is operated and the selector switch leaves the selected outlet. At the moment the "d" brush of the selector switch opens its contact, the alternating current potential is interrupted, and alternating current po-

tential will again be delivered to the rectifier. The direct current delivered by the rectifier, added to the potential from the potentiometer, is sufficient to ionize tube T_2 . The tube operates, the thyatron is again deionized and the selector switch stops. Relay Vtr now responds for the third time and energizes, this time via the alternate contact of relay Gbr the relay Vrr , which is locked via ground to front contact of relay Vtr .

The energizing of relay Vrr causes the release of relay Chr and tube T_2 extinguishes. After that, relays Gbr and Wlr will also release. The latter will restore tube T_2 to normal condition.

Upon the extinguishing of tube T_2 the relay Vtr releases, which in turn releases relay Vrr . This relay again applies ground to relay Chr , which operates. All other relays are de-energized, and the circuit is in the same condition as at the start of the hunting movement. By the charging of condenser C_1 relay Chr provides for the ionization of the thyatron and the control operation starts anew.

(b) During direct current testing, the alternating current potential disappears. This may be the case if two selectors test the same outlet simultaneously and the other selector seizes the outlet.

In this case tube T_2 will respond when relay Chr is energized and relay Str de-energized, because the absence of signaling current creates the required condition therefore in the energized condition of relay Wlr . The responding of tube T_2 will then have the same result as in the case described sub "a."

Figure 2 shows parts of a register controller and a selector switch, as described in the United States patent application Ser. No. 473,883. Here also the difference consists in that tube T_y , the condensers C_1 , C_{21} , C_{22} , C_3 and the resistances R_1 , R_2 , R_3 and R_4 are added, apart from some further small differences, which are mainly the same as in Figure 1.

The last mentioned application describes an arrangement whereby a selector switch is controlled by two signal receivers in the register controller, in such a way that if one of them responds, then the selector switch is caused to stop. Depending on the seized outlet and on the signal receiver, the register determines what the reaction should be to the seizure of this outlet.

In case the movements of the selector switch must be controlled by means of a thyatron, the problem arises how two or even more signal receivers may control these movements by means of thyatrtons. It is not possible to give each signal receiver its own thyatron as in the case shown in Figure 1, because each thyatron must independently control the movements of a selector. It is very difficult to control the magnet of a selector switch by several thyatrtons at the same time, because either the discharge spaces of the thyatrtons would have to be connected in series, in which case difficulties would occur upon the lighting of the tubes and very high battery potentials would be required, or the discharge spaces would have to be connected in parallel, which would simplify the lighting, but make impossible to de-energize the switch magnet upon the extinguishing of a single thyatron.

Figure 2 provides a solution by using a single thyatron, which is common to more than one signal receiver. As in the United States patent to Den Hertog No. 2,431,313, dated November 25, 1947, relay Chr has front contacts connected to the anode and cathode circuits of the two cold-

cathode tubes B_1 and B_2 and as in Figure 1 this is the same relay which charges via a front contact the condenser C_1 thereby producing in the thyatron the discharge condition when the wipers of the selector switch must be started to move.

The plate of the thyatron is now connected via two condensers C_{21} and C_{22} to the anode circuits of the two tubes B_1 and B_2 . As soon as one of these tubes is ionized as a result of finding by the selector switch of a free outlet in accordance with the reference current connected to one of the two signal receivers, the thyatron will be extinguished, either by a charge displacement of condenser C_{21} when tube B_1 responds, or by the charge displacement of condenser C_{22} when tube B_2 responds. The operation will now be briefly explained.

Let us assume that the reference current X connected to transformer T_1 of the upper signal receiver of Figure 2 is chosen in accordance with the called number digit designating the group of outlets to be selected, and the reference current Y is chosen in accordance with the designation of an alternative group. As soon as the selector is ready to start, a ground is connected via the brush a of switch OM . Relay Chr is operated, connects the tubes B_1 and B_2 and ionizes the thyatron by charging condenser C_1 . The switch power magnet P is energized in series with the thyatron. In case a desired outlet is found, the upper signal receiver responds and tube B_1 is ionized. Condenser C_{21} applies a negative charge to the plate of the thyatron, which is extinguished and stops the selector. Relay Vtr is operated in series with tube B_1 and this operates relay Ftr . Relay Ftr opens the circuit for relay Chr , which extinguishes tube B_1 and discharges condenser C_1 . Relay Vtr releases and operates relay Fhr , which now again operates relay Chr and causes a second alternating current test to take place. In case this test is successful, relay Vtr operates again and in turn operates relay Str , which now initiates the direct current test. In case the second alternating current test is not successful, relay Kir is operated via the back contact of relay Vtr and front contact of relay Chr , so that relay Vrr operates, which releases all operated relays and, after also relay Kir is released, will itself release and cause the hunting movement to start anew.

In case the direct current test is successful the relays Tr and Dtr operate, whereupon relay Sar is operated and the register is advanced to the position in which the setting for the next selection takes place.

If the direct current test is not successful, relay Gbr will operate via a front contact of relay Str and a back contact of relay Tr , as will also relay Wlr via a front contact of relay Gbr and a back contact of relay Vtr . Relay Str opens the circuit of relay Chr , so that tube B_1 is extinguished. Relay Wlr releases relays Ftr , Fhr and Str , whereupon the circuit of relay Chr is again closed.

Relay Wlr has in the meantime so changed the circuits of tube B_1 that it will respond only in the absence of signaling current. By the operation of relay Chr the thyatron is again ionized and the selector switch hunts until its brush d open the contact. Tube B_1 responds, extinguishes the thyatron and operates relay Vtr . This relay in turn operates relay Vrr , which releases all other relays, including Gbr and Wlr and finally releases itself and causes the selecting movement to start anew.

In case an alternative outlet is reached by the

selector switch, tube B_2 belonging to the second signal receiver responds. This causes the thyratron to extinguish by applying a negative charge to condenser C_{22} . At the same time relay V_{tr} is operated, which successively operates the relays V_{tr} and F_{tr} . Relay V_{tr} locks itself to ground under the control of relay V_{rr} and establishes the circuits for the second signal receiver. The register must respond accordingly, e. g. by effecting of an additional selector setting. This starts only if a second alternating current test and the direct current test are successful. These operations take place in the same way as described above. After the operation of relay D_{tr} , not relay S_{ar} , but relay V_{tr} operates and locks itself independently of V_{tr} via the front contact of relay D_{tr} and energizes relay V_{rr} . The latter releases all other relays, except relay S_{tr} , which remains operated via a front contact of relay V_{tr} , so that the relays T_{tr} and D_{tr} may release only if the free test potential on the seized outlet is opened. Then these relays will release, as will also V_{tr} , V_{rr} and S_{tr} and a next selector setting may start. As relay O_{tr} was energized via a front contact of relay V_{tr} , the conditions for this selector setting under the control of relay O_{tr} are changed. The seized bypass selector may choose an outlet which leads to the desired group.

If the second alternating current test does not result in the seizing of the alternative outlet, then relay K_{tr} responds in the known way, and by means of relay V_{rr} causes the hunting movement to start anew. Relay V_{tr} is then also de-energized by relay V_{rr} .

If after the seizing of the alternative outlet the direct current test is not successful, relay G_{tr} , and under the control of a front contact of relay V_{tr} , relay W_{tr} will also respond. Relay W_{tr} switches the elements of the second signal receiver in such a way that tube B_2 may now only respond in the absence of signaling current, i. e. as soon as the selector switch has left the contact of the seized alternative outlet. The balance of the operations take place in the same way as described above.

What is claimed is:

1. In an electrical control system, a variably operable register switch, a plurality of selector switches variably operable in accordance with the operation of said register, each selector having an operating magnet, a control circuit therefor, a plurality of multi-electrode discharge tubes in the register, a first one of said tubes having electrodes in said control circuit, a circuit for controlling a second one of said tubes controlled by the selector, and a control circuit for the first tube controlled by the second tube.

2. The system according to claim 1, and in which the control circuit of the magnet includes in series the discharge space of the first tube, the operation of a selector being started by the ionization of the discharge space, a grid in the first tube controlling the discharge space, and a condenser connected to said grid.

3. In an electrical control system, a variably operable register switch, a plurality of selector switches variably operable in accordance with

the operation of said register, each selector having an operating magnet, a control circuit therefor, a plurality of discharge tubes in the register, each tube having a cathode and an anode electrode and a grid controlling the discharge path between said electrodes, a first one of said tubes controlling said control circuit in which the discharge path is included in series, a condenser connected with the grid of the first tube, a circuit for controlling the grid of a second one of said tubes controlled by the selector, and a circuit controlling the charging of said condenser controlled by the second tube.

4. The system according to claim 1, and means in the control circuits of the magnet and of the first tube for causing the successive energization and de-energization of the magnet.

5. The system according to claim 1, and in which the control circuit of the magnet includes a resistance, and a condenser in parallel with said resistance.

6. The system according to claim 3, and in which the control circuit of the magnet includes the magnet winding, and in series therewith a resistance and the anode and cathode of the first tube, and a condenser in parallel with said resistance.

7. The system according to claim 1, a condenser connected with one of said electrodes in the control circuit of the magnet, and means controlled by the second tube for charging said condenser.

8. The system according to claim 3, and a resistance shunt around said condenser.

9. The system according to claim 3, a condenser connected with the anode of the first tube, and means controlled by the second tube for charging the last-mentioned condenser.

10. The system according to claim 1, and a gas valve between the first and second tubes for relaying the operation of the latter.

11. The system according to claim 1, a plurality of second tubes, each arranged to be controlled by the selector, and means for connecting the control circuit of the first tube with the second tube operated by the selector.

12. The system according to claim 3, a plurality of second tubes, each arranged to be controlled by the selector, a gas valve associated with each second tube and operable under its control, and a connection including a condenser between the anode of the first tube and the anode of each gas valve.
